STORAGE RACK FOR WINE BOTTLES OR THE LIKE

Eugene J. Maiewski, 121 Elmore St.,
Park Ridge, Ill. 60068

Filed Jan. 18, 1972, Ser. No. 218,853

Term of patent 14 years

Int. Cl. D6—04

U.S. Cl. D7—71

FIG.1

FIG.2

FIG. 3

FIG. 4

FIG. 1 is a top plan view of a storage rack for wine bottles or the like showing my new design.

FIG. 2 is a front elevation view thereof.

FIG. 3 is a side elevation view thereof.

FIG. 4 is a perspective view thereof.

I claim:

The ornamental design for a storage rack for wine bottles or the like, as shown.
